TIME DELAY RELAY

Charles M. Lubcke, Seattle, Wash., assignor to
Kirsten Lighting Corporation, Seattle, Wash.

Application May 5, 1936, Serial No. 77,950

2 Claims. (Cl. 175—320)

This invention relates to time delay switches or relays, and it has reference more particularly to devices of that character that are especially suited for use in connection with the operation 5 of hot cathode luminous arc lamps and similar gaseous discharge devices, wherein it is desirable to bring the cathodes up to a certain degree of heat before applying the potential whereby the arc between electrodes is kindled; it being recognized that it is injurious to the cathodes to initiate an electrical discharge between them before they have had sufficient time to heat up.

It is the principal object of this invention to provide a time delay relay that is extremely accurate with respect to its time interval; which is not affected by climatic conditions or temperature changes; which is inexpensive in construction, simple in detail and effective and efficient in its action.

20 A further object of the invention resides in the construction of and in the combination of parts, and in the method of use of the device, as will hereinafter be fully described.

In accomplishing these and other objects of 25 the invention, I have provided the improved details of construction, the preferred forms of which are illustrated in the accompanying drawing, wherein—

The single view is a diagrammatic illustration 30 of the present time delay relay, together with the electrical circuits whereby it is functionally connected with a luminous arc lamp.

It is to be understood that the present device, while herein illustrated in its connection with a 35 luminous arc lamp, is adapted also to various other uses where time delayed action is desired; the combination herein illustrated being merely explanatory to the use of the relay, and it is not intended that the illustration shall in any way limit the use of the relay to lamps or similar devices.

Referring more in detail to the drawing—

A source of electrical current is designated at S, from which supply lines 2 and 3 lead to a line 45 switch 4 whereby circuit connection may be closed or opened with main lines 5 and 6, which supply current to the device under control.

The time delay relay embodied by the present 50 invention is designated in its entirety at R, and it comprises a solenoid coil 7 containing a movable plunger 8 to which a plurality of switch bars are fixed. In the present instance, the bars are designated, respectively, by the reference numerals 9, 10, 11 and 12, and it is to be understood 55 that they are insulated from each other and from

the plunger and move with the plunger under influence of the solenoid.

The switch bar 9, which is the lower one, as herein illustrated, is adapted in one position of the plunger 8, that is, the de-energized position 5 of the solenoid, to engage at its opposite ends with spaced contacts 13—13'. When the plunger is moved upwardly incident to energizing the solenoid coil 7, the bar 9 will likewise engage with spaced contacts 14—14'.

10 The contacts 13' and 14' are both connected by wires, designated at 15, with the main line wire 5, while the contacts 14 and 13 are connected, respectively, by wires 16 and 17 with a switch contact 18 and a yieldably movable switch 15 lever 19; the latter being normally disengaged from the contact 18, but is movable thereagainst, by means presently described, to close a circuit connection between them.

The solenoid coil 7 has circuit connections 20 20 and 21 connecting its opposite ends, respectively, with the main line 6 and circuit wire 16.

Associated with the movable switch lever 19 is a revolvably mounted cam 25 on a revolvably driven gear 26 that is operatively connected through a 25 speed reduction worm 27 on the driven shaft of an electric motor 28. The motor 28 has circuit connections 29 and 30, respectively, with the main line 6 and with the circuit wire 17. Thus, with the closing of main switch 4, a circuit will 30 be closed through the motor 28, and the cam 25 will be rotated incident to energization of the motor. The motor circuit in this instance will flow from main line 6 through wire 29, motor 28, wire 30, wire 17, contact 13, bar 9, contact 35 13', wire 15, to main line wire 5.

The cam 25 has one or more lobes 25' projecting from its periphery and these are adapted, incident to rotation of the cam, to move into contact with the lever 19 in a manner whereby 40 to move the lever outwardly against the stationary contact 18, thus to cause a circuit to be closed through the solenoid coil 7; the circuit flowing from main line 6 through wire 20, coil 7, wire 21, wire 16, contact 18, lever 19, wire 17, 45 contact 13, bar 9, contact 13' and wire 15, to line wire 5.

Incident to closing a circuit through the solenoid coil 7, the plunger 8 will be lifted, thereby causing bar 9 to break the circuit connection between the contacts 13 and 13' and immediately closing the connection between the contacts 14 and 14' by the bar 9. Thus, the current now flows through the coil 7 to retain the plunger 8 in its raised position; the current flowing from line 55

wire 6, through wire 20, coil 7, wire 21, wire 16, to contact 14, bar 9, contact 14' and wire 15, to main line wire 5. The current to the motor at this time flows from line wire 6, through wire 5 29, motor 28, wire 30, wire 17, to lever 19, contact 18, wire 16, contact 14, bar 9, contact 14', wire 15, to main line 5.

When the lever 19 is released incident to that movement of cam 25 which disengages the lobe 10 25' therefrom, the connection between the lever 19 and contact 18 is immediately broken. Therefore, the circuit connection for the motor 28 is 15 opened and the cam stops rotating. The time interval between the time of closing the main switch 4 and the energizing of the solenoid coil 1 7 is determined by the cam action; that is, by its speed of rotation, the spacing of the lobes thereon, and the relation of the path of travel of the lobes to the switch lever 19, and these 20 factors may be varied in accordance with the requirement for any special timing operation, as should be quite apparent.

For the purpose of illustrating the use of the present time delay relay, I have shown, in combination therewith, a hot cathode luminous arc tube 30 provided within its opposite ends with electrodes 31-31'. These electrodes are connected, respectively, in circuit with the secondary coils 32-32' of a transformer designated in its 30 entirety at 33, the primary coil 34 of which is connected in circuit with the line wires 5 and 6 by wires 35 and 36. Also, associated with the lamp 30 is a power transformer designated at 40 having its secondary coil 41 connected, respectively, by wires 42 and 43 with the electrodes 31 and 31' and having its primary coil 44 connected by wires 45 and 46, respectively, with line wires 5' and 6', which, through the relay, may be connected with the main line wires 5 and 6, 40 as will now be described.

It will be observed that, adjacent the opposite ends of the cross bar 10, are contacts 50 and 50'. Likewise, adjacent the opposite ends of the cross bar 11 are contacts 51 and 51'. The line wires 45 5 and 6 connect, respectively, with the contacts 50' and 51', and the wires 5' and 6' connect, respectively, with the contacts 50 and 51. The relationship of the cross bar 10 to the contacts 50-50', and the relationship of cross bar 11 to the contacts 51-51', in each instance, is such that when the plunger 8 is in lowered position, that being the position it assumes when the coil 7 is deenergized, the circuit connections between wires 5-5' and 6-6', is open. However, upon 55 energization of the coil 7, and the lifting of plunger 8, the cross bars 10 and 11 are thereby brought into engagement with the paired contacts, and the circuits are closed. Thus, the energization of coil 7 moves the plunger to effect the 60 closing of a circuit through the transformer 40 to apply the operating potential to the lamp 30.

Assuming that the parts are assembled, and are electrically connected as shown in the drawing, and assuming also that the line switch 4 is 65 open and that the position of the cam 25 is such that the switch lever 19 is disengaged from the contact 18 and that the cross bar 9 is engaged with contacts 13-13', and that the other cross bars are disengaged from their respective contacts, operation of the device would be as follows:

Upon closing the line switch 4, the motor 28 is energized by reason of current flowing from wire 6 through wire 29, motor 28, wire 30, wire 75 17, contact 13, bar 9, contact 13' and wire 15,

to the line wire 5. Also, upon closing the switch 4, the transformer 33 is energized through the connections 35 and 36 and a heating current is caused to flow through the electrodes 31 and 31'. After a predetermined time interval, a lobe 25' of the rotating cam 25, engages the lever 19 and moves the latter to close circuit connection between the contact 18 and lever 19; thereby energizing the coil 7, since current will then flow from line wire 6 through the wire 20, coil 7, wire 21, wire 16, contact 18, lever 19, wire 17, contact 13, bar 9, contact 13', wire 15, to line wire 5. Upon energization of the coil 7, the plunger 8 is lifted, thereby causing the bars 10 and 11 to engage their respective contacts, 50-50' and 51-51', thereby closing the circuit to the power transformer 40, resulting in an application of operating potential to the electrodes 31-31' of the lamp.

It is to be understood that when the cross bar 20 9, which operates as a double acting switch, is lifted by the plunger to engage with the contact 14-14', the current is shunted around the timing switch and then flows from the line wire 6 through the coil 7, wire 21, contact 14, bar 9, 25 contact 14' and wire 15, to the line wire 5, thus holding the plunger in raised position as long as switch 4 is closed. However, the motor circuit is shunted through the timing switch and the motor stops incident to opening of the circuit 30 between contact 18 and lever 19.

Upon opening line switch 4, the solenoid 7 is de-energized and the plunger 8 drops to initial position, as seen in full lines in the drawing.

The cross bar 12 on the plunger 8 merely is 35 to indicate the provision for closing of additional circuits by the action of the timing means, and it is further apparent that other solenoids might be connected either in series or in parallel with that here shown for operation of additional 40 switches.

Time delay switches of this kind have many uses. They are useful with any hot cathode tube having an oxide coating, and also are useful in radio receivers and in various other devices 45 where one part is operated after a certain time interval with reference to the operation of another.

Having thus described my invention, what I 50 claim as new therein and desire to secure by Letters Patent is—

1. In combination, main circuit lines, a line switch operable to connect the said main circuit lines with a source of current, a control switch for a device in the main circuit, a relay for actuation of the control switch having circuit connections at opposite sides, respectively, with the main circuit lines, a normally open timing switch in one of said connections, a normally open shunt connection across the timing switch, a double acting switch connected for actuation by the relay and normally positioned to complete the circuit connection between the timing switch and the corresponding main circuit line, and adapted, when actuated to its other position, to open that connection and maintain the relay circuit through the shunt connection independently of the timing switch, an electrically operated timing mechanism having a circuit connection at one side with one of the main circuit lines, and having a circuit connection at the other side with the circuit connection between the timing switch and double acting switch, and adapted to be energized upon closing the line switch, means operable by the timing mechanism to close the tim- 75

ing switch to energize the relay, thereby to effect closing of the control switch and actuation of the double acting switch to close the shunt connection and divert the circuit of the timing mechanism through the timing switch.

5 2. The combination with lines of a main circuit and a control switch in the main circuit, of a relay for actuating the control switch between open and closed positions, and adapted, when 10 energized, to retain the control switch in closed position, an electrically actuated timing device including a motor and a motor circuit connected across the main circuit, a primary and a shunt energizing circuit for the relay, each connected 15 across the main circuit; said primary circuit including a normally open timing switch adapted to be closed and opened under control of the said

timing device, and a double acting switch also connected with the said primary and shunt circuits and movable by the relay with the opening and closing movements of the control switch and adapted, in the open position of the control switch, to close the motor circuit to energize the timing device independently of the timing switch, and to place the primary circuit of the relay under control of the timing switch, and adapted, in the closed position of the control 10 switch, to shunt the circuit of the relay through the said shunt circuit and to close the circuit of the motor through the timing switch whereby the relay will remain energized and the circuit of the timing device will be opened incident to 15 opening of the timing switch.

CHARLES M. LUBCKE.
